UNITED STATES PATENT OFFICE

123,666

DESIGN FOR A WASHING MACHINE TUB OR SIMILAR ARTICLE

Robert M. Chesney, Alliance, Ohio, assignor to
The Alliance Porcelain Products Company, Alliance, Ohio, a corporation of Ohio

Application May 6, 1940, Serial No. 92,183

Term of patent 3½ years

To all whom it may concern:

Be it known that I, Robert M. Chesney, a citizen of the United States and a resident of Alliance, county of Stark, and State of Ohio, have invented a new, original, and ornamental Design for a Washing Machine Tub or Similar Article, of which the following is a specification, reference being had to the accompanying drawing forming part thereof.

In the drawing—

chine tub or similar article showing my new design; and

Figure 2 is a fragmentary side elevational view thereof with the bottom portions broken away for convenience of illustration.

I claim:

The ornamental design for a washing machine tub or similar article, substantially as shown and described.

ROBERT M. CHESNEY.
